UNITED STATES PATENT OFFICE.

CHARLES WHITTAKER, OF CHICAGO, ILLINOIS.

FAUCET.

SPECIFICATION forming part of Letters Patent No. 257,538, dated May 9, 1882.

Application filed October 5, 1881. (No model.)

To all whom it may concern:

Be it known that I, CHARLES WHITTAKER, a citizen of the United States, residing at Chicago, in the county of Cook and State of Illinois, have invented certain new and useful Improvements in Faucets; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My invention consists, first, in the application of a screw in connection with that class of stoppers which are opened against the current or pressure and closed in front of the current or pressure of the water, whereby the water and screw act together in retaining the stopper in its closed position, and whereby said stopper may be more gradually opened and closed, and the danger of bursting the pipes by too suddenly stopping the flow of water avoided; second, in forming the valve-seat at or near the mouth of the coupling-stem, where it may be more conveniently reamed out and fitted to the stopper; third, in locating the interior mechanism below the body of the faucet and supporting-slab, whereby it becomes unnecessary to provide so much space for the same above the slab, and in reducing the height of the faucet to conform to the reduced space required.

My invention is further explained by reference to the accompanying drawings, in which—

Figure 1 represents a longitudinal vertical section. Fig. 2 is a transverse section drawn on line *x x* of Fig. 1.

Like parts are represented by the same reference-letters in both views.

A is the valve-seat, which, being near the mouth of the coupling-stem *B*, is easier formed, and the interior of the faucet may be left as cast, without fitting or cutting, whereby the construction of the faucet is greatly simplified. The valve or stopper *G* is rigidly connected with the sliding sleeve *D* by the short stud or connecting-rod *E*, both of which are located below the spout *c*, by which arrangement of the parts I am enabled to connect said spout lower down at or near the slab *I*, as shown,

and thus greatly reducing the height of the faucet, making it more compact in form, neater in appearance, when it is less in the way, and requiring less labor in finishing and less material for construction. The sleeve *D* and stirrup *H* are cast in the same piece.

Heretofore it has been common to locate the screw, sliding sleeve, stirrup, and compression-valve above the slab, which valve, thus located, is adapted to act against the water when closing the faucet. By thus locating such parts above the supporting-slab it is obvious that it became necessary to extend the faucet upward to accommodate them, while by my improvement in construction and arrangement of the parts this necessity is obviated, and the faucet may be made much smaller.

E' is the valve-stem, which communicates between the handle and the sleeve, and is connected with said sleeve by a screw which causes the sleeve and stopper to move upward and downward as the handle *F* is turned toward the right and left. The sides of the sleeve *D* are provided with flanges, which move in ways formed in the walls of the faucet and serve as guides to the sleeve, while they prevent the sleeve from turning with the screw.

It is obvious that when the stopper *G* is opened by the action of a screw, as shown, the water is permitted to escape gradually at first, and the required flow may be produced without spattering the water, while it is obvious that were the stopper thrown widely open with one partial turn of the handle the water would escape with too great force. It is also obvious that when closing the faucet too suddenly under high pressure there arises danger of bursting the pipes, which danger is also obviated by the gradual action of the screw described.

Having thus described my invention, what I claim as new, and desire to secure by Letters Patent, is—

1. In faucets, the combination of the body *F*, provided with the spout at or near the supporting-flange, valve-rod *E'*, extending from the handle to the sliding sleeve *D*, sliding sleeve *D*, stirrup *H*, connecting-rod *E*, valve *G*, coupling-stem *B*, and valve-seat *A*, all substantially as set forth.

2. The combination of handle *F'*, valve-rod *E'*, sleeve *D*, stirrup *H*, said valve-rod being

connected to said sleeve by a screw, by which said sleeve and stirrup are moved upward and downward as said handle is turned toward the right and left, rod E, valve G, and valve-seats 5 A, substantially as set forth.

3. In faucets, the combination of the stopper or valve G, adapted to be closed with instead of against the pressure of water, and the screw-cut valve-rod E, said stopper and screw 10 being connected together by sleeve D, stirrup

H, and connecting-rod E, whereby the said valve is gradually opened and closed by the action of the screw, all substantially as set forth.

In testimony whereof I affix my signature in presence of two witnesses.

CHARLES WHITTAKER.
